UNITED STATES PATENT OFFICE.

WALTER AUTHER BERRY, OF CHATTANOOGA, TENNESSEE, ASSIGNOR OF ONE-HALF TO
RAYMOND W. FRAWLEY, OF CHATTANOOGA, TENNESSEE.

BOILER.

No. 913,681.

Specification of Letters Patent.

Patented March 2, 1909.

Application filed May 11, 1908. Serial No. 432,192.

To all whom it may concern:

Be it known that I, WALTER A. BERRY, a citizen of the United States, residing at Chattanooga, in the county of Hamilton and 5 State of Tennessee, have invented new and useful Improvements in Boilers, of which the following is a specification.

This invention relates to boilers of the water tube type, and has specially in view 10 certain improvements therein which will cause the heat and other products of combustion to pass over and about all the water tubes so as to assure of the same being kept in a highly heated condition.

15 With the above and other objects in view, the invention contemplates the production of a boiler of the horizontal type comprising an outer shell and an inner shell, the inner shell being held in spaced relation to the outer 20 shell so as to provide water spaces which practically surround the same, and in further equipping the inner shell with a plurality of crossing water tubes arranged in checkered relation, which, in conjunction with a novel 25 form of bridge wall and depending water pocket, cause the heat from the fire chamber to be deflected over and about all the said water tubes.

In the practical application of the invention 30 many changes in detail and structural arrangements may be resorted to, a practical and preferred embodiment of which is shown in the accompanying drawings, in which—

Figure 1 is a front view of the boiler, 35 showing the arrangement of the clean-out openings in the outer shell. Fig. 2 is a longitudinal vertical sectional view of the same. Fig. 3 is a cross sectional view, taken on the line 3—3, Fig. 2. Fig. 4 is a similar 40 view taken on the line 4—4, Fig. 2.

Like characters of reference designate corresponding parts.

It is preferred to associate the present invention with the type of boiler known as 45 the "horizontal," and the same comprises an outer shell or casing, the front sheet 1 of which has the usual lower draft door 2, and fuel door 3, and above the same said front sheet 1 has formed through it a plurality of 50 horizontally arranged clean-out openings 4, which are kept tightly sealed through the medium of arched caps 5 and coöperating locking bolts 6 carrying spiders 7 which engage the inner surface of the said front sheet.

55 The rear sheet 8 of the outer shell is simi-

larly equipped with clean-out openings 9, sealing caps 10 and coöperating bolts 11 carrying fastening spiders 12, and preferably the clean-out openings in the front and rear sheets are in alinement. The upper portions 60 of each of said front and rear sheets are held in a rigid relative position through the medium of a plurality of connecting bolts 13 which are held in engagement with each sheet by lock nuts 14—15, respectively. 65

The vertical side sheets 17—18 and the arched top sheet 19 are preferably integral, and to facilitate connection therebetween and the front and rear sheets, the latter are provided with upper and lower inturned 70 flanges 20—21, which are bolted, or otherwise secured to the edges of said top and side sheets, as indicated at 22—23. The side sheets 17—18 have formed through them a plurality of longitudinally arranged rows of 75 clean-out openings 23—24, sealing caps 25—26, and locking bolts 27—28 and spiders 29—30, which are of the same type as those described in connection with the front and rear sheets, but for the purpose which will 80 presently appear, the clean-out openings in the side sheets are arranged in different planes from those in the front and rear sheets, so that each row therein will alternate with the rows in said front and rear sheet, 85 as is more clearly shown in Fig. 1 of the accompanying drawings.

Referring more particularly to Fig. 2 of the accompanying drawings, it will be observed that the front portion of the arched 90 top of the outer shell has formed through it an opening 31 around which is seated a threaded nipple 32 adapted for the attachment of the usual steam conveying pipe not shown, and adjacent to said steam exit opening a manhole 33 is formed through the said arched top, the inner edge of which has a depending flange 33^a which engages the spider 34 of a locking bolt 35 carried by an arched sealing cap 36 which engages the 100 outer surface of the said arched top sheet, when the locking bolt is manipulated to cause its spider to engage with the inner depending flange 33. The said arched top is also provided with an opening 37 over which 105 is fitted a flanged and threaded nipple 38 to which is fitted the usual safety valve, not shown. The rear portion of the arched top has formed through it an enlarged and preferably circular opening 39 the edge of which 110

carries an annular angular reinforcing strip and holding strip 40 which serves to hold therein a smoke pipe 41.

The bottom sheet 42 of the boiler at approximately its midlength, is provided with a manhole 45 which has formed around its interior edge an annular angular flange 46 which a locking spider 47 carried by a locking bolt 48 engages to retain an arched cap 10 49 over the outer side of said manhole.

The inner side of the arched top sheet of the boiler is provided with a plurality of channeled irons 50 which carry depending stay bolts 51 the lower ends of which are 15 rigidly connected with angle irons 52 carried by the crown sheet 53 of an inner tube shell 54. Said inner shell 54 is provided with front and rear sheets 55—56 which have a plurality of rows of horizontally arranged 20 openings 57—57 which are in alinement with the clean-out openings formed in the front and rear sheets. The crown sheet 53 adjacent to its rear end is provided with an opening 58 to the edge of which is bolted the 25 flanged open top 59 of a depending water pocket 60, the side walls of which have formed through them a plurality of horizontally arranged openings 60—61 which are in alinement with the rows of openings formed 30 in the front and rear sheets of the inner shell and are adapted to receive the ends of longitudinal water tubes 62—63 the other ends of which are supported within the openings in the front and rear sheets. Immediately 35 in the rear of the pocket opening in the crown sheet, another opening 64 is formed which communicates with the lower end of the smoke pipe and around the same an annular flanged connecting and reinforcing 40 iron 65 is seated which has a bolted connection with said crown sheet and said smoke pipe. The side sheets 66—67 of the inner shell are provided with a plurality of rows of longitudinally arranged openings 68—69 45 which are in alinement with the clean-out openings formed in the side sheets of the outer shell and have the ends of the crossing water tubes 70 seated therein. The bottom sheet 71 of the inner shell has its ends se- 50 curely fastened to inturned flanges carried by the end sheets of the inner shell, and at approximately its midlength it has formed therein an opening 72 around which is mounted the flanged entrance 73 to a hol- 55 low bridge wall 74 the rear wall of which has openings 75 formed therein which aline with the openings formed in the lower portion of the rear sheet of the inner casing and which receive the ends of short-length water 60 tubes 76.

Immediately in front of the hollow bridge wall a space is left in the inner casing for a fire chamber 78 provided with the usual grate 79 and lower opening 80 communicat- 65 ing with the draft door and upper opening 81

communicating with the fuel door. The top and bottom of the fuel opening is sealed by means of the inserted flanged plugs 82—83 and the draft opening is also similarly sealed at its top and bottom by plugs 84.

In order to assist in retaining the inner shell in a regularly spaced apart relation to the outer shell end stay bolts 86 and side stay bolts 87 are employed, as is usual in boiler construction.

From the foregoing description it will be seen that the space between the two shells is utilized for holding water and through the medium of the crossing pipes there is at all times a communication with said water spaces. And it will be further seen that when the products of combustion leave the fire chamber they will be deflected upward by the hollow bridge wall and caused to pass over and about the crossing pipes through 80 the checkered openings therebetween, until they reach the water pocket by which they will be deflected downward and over and about the lower short length tubes and thence upward through the upper tubes and out 85 through the smoke pipe. This arrangement of deflectors in the path of movement of the products of combustion assures of all tubes being acted on by the heating agents, and as 90 said deflectors are all hollow and contain 95 water, such water therein is also kept in a highly heated condition.

What I claim is.

1. A boiler comprising an outer shell, an inner shell held in spaced relation to said outer shell and being provided with a plurality of rows of crossing water tubes, a hollow bridge wall carried by the lower portion of said inner shell, and a depending water pocket carried by the upper portion, said bridge wall and said water pocket being so arranged relatively that the heating agents will be deflected thereby on its passage through said inner shell.

2. A boiler comprising an outer shell, an inner shell held in rigid relative spaced relation to said outer shell, and being provided with a plurality of rows of longitudinal and lateral crossing water tubes, an upstanding hollow bridge wall carried by said inner shell 110 and a depending water pocket also carried by the inner shell, said water pocket and said bridge wall being arranged in the path of movement of the heating agent and adapted to deflect the same through various parts of 115 the inner shell.

3. A boiler comprising an outer shell the walls of which are provided with clean-out openings, an inner shell held in spaced relation to the outer shell and being provided 125 with a plurality of tiers of longitudinal and lateral water tubes, the ends of which aline with the openings formed in the said outer shell, and upper and lower hollow deflectors arranged within the inner shell and adapted 130

to deflect the products of combustion to various parts of the same.

4. A boiler comprising an outer shell and an inner shell held in relative spaced relation to provide water spaces therebetween, crossing water tubes carried by the inner shell the ends of which communicate with said water spaces, a hollow water pocket in communication with said water spaces and also with one end of a portion of the water tube, and a hollow bridge wall also in communication with

the water spaces and some of the water tubes, said water pocket and bridge wall being located in the path of movement of the heating agent and adapted to deflect the same to various parts of the inner shell.

In testimony whereof, I affix my signature in presence of two witnesses.

WALTER AUTHER BERRY.
